UNITED STATES PATENT OFFICE.

RICHARD STRAUBEL, OF NEW YORK, N. Y.

EYEGLASSES.

SPECIFICATION forming part of Letters Patent No. 349,413, dated September 21, 1886.

Application filed April 19, 1886. Serial No. 199,319. (No model.)

To all whom it may concern:

Be it known that I, RICHARD STRAUBEL, of the city, county, and State of New York, have invented certain new and useful Improvements 5 in Eyeglasses, of which the following is a specification.

This invention relates to eyeglasses of that class provided with spring nose-pieces and a connecting bow-spring; and the invention consists of a pair of eyeglasses which are provided with nose pieces, the lower ends of which are attached to clips of the glasses, while the upper ends are slotted and guided in clips at the upper parts of the glasses, said clips having 10 seats or shoulders for the ends of the bow-spring, which ends are attached by screws that serve, in connection with the space below the shoulders of the clips, to guide and stop the flexible nose-pieces, as will more fully appear 15 hereinafter, and finally be pointed out in the claim.

In the accompanying drawings, Figure 1 represents a side elevation of my improved eyeglasses. Fig. 2 is a vertical longitudinal 20 section through one of the upper clips, drawn on a larger scale; and Figs. 3 and 4 are a horizontal section and a vertical transverse section, respectively, on line *y y* and *x x*, Fig. 2.

Similar letters of reference indicate corresponding parts.

Referring to the drawings, *a a* represent the flexible nose-pieces, the lower ends of which are attached to clips *b'* of the frame *b* of the glasses or to the glasses themselves. The nose-pieces 35 *a a* are made of any approved construction, the upper parts, *a'*, being bent in opposite direction to each other and provided with slots *a''*. The upper ends, *a'*, are guided in clips *d*, that are soldered or otherwise attached to 40 the upper part of the frames *b b* or directly to the glasses. The upper clips, *d d*, are made of U-shaped cross-section, their side flanges being provided below the edges with inwardly-projecting shoulders or seats *d'*, that serve 45 to support the ends of the connecting-bow or bridge-spring *e*, which ends are attached to

the upper clips, *d d*, by screws *d''*. The slotted upper ends of the nose-pieces *a a* are guided in the spaces formed between the shoulders *d'* and the bottom of the clips *d*, while the 50 screws *d''* serve as stops for stopping the nose-pieces and limiting their movement in either direction. The screws *d''* serve a twofold purpose—that of attaching the ends of the bow-spring to the clips *d d*, and that of guiding and 55 stopping the outer slotted ends of the nose-pieces.

I am aware that eyeglasses with flexible nose-pieces the upper ends of which are capable of lateral movement are well known, and 60 I therefore do not claim this feature, broadly; but in these cases the upper ends were either not guided at all, or guided in such a manner that projecting portions are formed on which the handkerchief is caught when cleaning the 65 glasses. The objection is entirely avoided by my construction, which has no projecting parts, and in which eyeglasses represent a regular and symmetrical appearance, as the nose-pieces are guided in the supporting-clips of the bow- 70 spring.

Having thus described my invention, I claim as new and desire to secure by Letters Patent—

The combination of the flexible nose-pieces, attached at their lower ends to clips of the eyeglasses, and having slotted upper ends, guide-clips attached to the upper part of the glasses, said clips having inwardly-projecting shoulders or seats, a bow-spring, the ends of which rest on said shoulders, and screws for fastening the ends of the bow-spring to the clips and retaining the slotted ends of the nose-pieces in the guide spaces below the shoulders of the clips, substantially as set forth.

In testimony that I claim the foregoing as 85 my invention I have signed my name in presence of two subscribing witnesses.

RICH. STRAUBEL.
